UNITED STATES PATENT OFFICE.

THOMAS HOLT, OF TARRYTOWN, NEW YORK.

EGG-BEATER.

SPECIFICATION forming part of Letters Patent No. 631,715, dated August 22, 1899.

Application filed March 2, 1899. Serial No. 707,509. (No model.)

To all whom it may concern:

Be it known that I, THOMAS HOLT, of Tarrytown, in the county of Westchester and State of New York, have invented a new and useful Improvement in Egg-Beaters, of which the following is a specification.

My invention is in the nature of a device for beating eggs, cream, or material for cakes which is designed to accomplish its result more quickly and effectively and without leaving any unbeaten residuum in the bottom of the vessel.

It is an improvement upon that form of beater in which two rotating beater-bows are arranged side by side on different axes eccentric to each other and in rotating work one into the other; and it consists in the peculiar construction and arrangement of parts, which I will now proceed to more fully describe, reference being had to the accompanying drawings, in which—

Figure 1 is a side elevation; Fig. 1^a, an enlarged end view of the handle, partly in section. Fig. 2 is an enlarged top view; Fig. 3, a section through line 3 3 of Fig. 1, and Fig. 3^a a section through line 3^a 3^a. Figs. 4, 5, 6, and 7 are details; and Figs. 8, 9, and 10 are side views showing modifications of the rotating beaters.

In the drawings, A A are two rotating dashers or beater-bows arranged side by side on independent axes B B, eccentric to each other, and formed by a single stout bent wire. The beaters have at their upper ends two intermeshing gear-wheels a a, which are turned in an opposite direction by a crown-wheel C through a crank-handle D. This general form of beater is as so far described already in use.

I will now proceed to describe the novel features of my invention.

The beaters A have each a circular portion a' and a shank portion a², which in this instance are stamped out of a flat piece of sheet metal in a single piece. The lower circular portion of the beater is stamped with an offsetting lug a³, which is perforated to receive one of the axial bars B, and the upper ends of the shanks are rigidly fastened to the two small gear-wheels, which being perforated and inclosing the axial bars form the upper bearings for the rotating beaters. The cir-

cular portion a' of the beater has its two opposite sides bent so as to stand neither radial to the center of revolution nor yet at right angles to the radius, but at an angle between these two positions, as shown in Fig. 3, in which the plane of the blade from the bottom to the top of the bow crosses the circumferential path indicated in dotted lines, with its outer edge in advance or leading. The purpose of this is to cause the inclined blades to gather the material and throw it into the center. The upper portion of the beater a² is stamped to a curved form in cross-section, as seen in Fig. 3^a. The object of this is twofold—first, to give by its hollow or corrugated form a longitudinal stiffness, and, secondly, to cause the shank portion in rotating about its axial rod to pass edgewise through the material with the least possible resistance, and this it does by being curved transversely to the arc of a circle described about the axial rod.

E is the handle of the beater. This is made from a flat bar of metal bent in the middle into an elliptical bow and having its two ends extended downwardly and connected rigidly to the axial rods B B, as hereinafter described. The elliptical loop portion of the handle is specially constructed to give a firm grasp in the palm of the hand, and for this purpose the metal of the bar is split longitudinally (see Fig. 1^a) and then spread apart to form two bows e e, which are then connected together on top by a broad flat plate e', which is stamped of sheet metal and applied to the two bows e e by means of clips or flanges e² e³, bent around the bows and tightly pressed thereupon, so as to form a firm and rigid connection. This holds the bows to their proper spread and gives a broad bearing for the hand for holding the beater steadily when turning the crank.

The lower part of the two branches of the handle and the upper ends of the axial rods B B are rigidly connected together, and for this purpose I form a metal block F (see Fig. 4) with a hole f through it and with seats f'. In these seats the upper ends of the rods B B, which are curved to correspond, are clamped between the block and the lower ends of the handle-bars by means of a bolt or rivet f². This when tightened up firmly clamps the handle and the axial rods to

gether, so that they cannot become loose or detached. To further fix the block in place against turning on the bolt f^2 , a half-round seat f^3 (or a perforation) is formed in the upper end of the block, which receives a second bolt f^4 , that forms the axis of the large gear-wheel.

In Fig. 8 I show a modification of the beater-bows. These are made from a straight strip of material and have two shanks connecting with each driving-wheel. This I regard as the most simple and practical form of making the bows. For connecting them to the gears the latter are formed with square hubs m , Figs. 5 to 8, with little indentations m' . Into these indentations fit the inturned ends m^2 of the upper ends of the beater-shanks, and a square ferrule or thimble m^3 , pressed upwardly over the ends of the shanks, secures them rigidly to the gears. This same connection may be employed with the single shank shown in Fig. 1; but I do not confine my invention to this special form of connection, as the shanks and the gears may be connected together in various simple and practical ways.

In Fig. 9 is shown another modification of the beater-bows. This only differs from that shown in Fig. 8 in the following particulars: In Fig. 8 the angular position of the bow from bottom to top is the same and is arranged to gather the material and throw it inwardly. In Fig. 9 the blade of the bow is given a spiral twist, which causes the lower half of the bow to gather the material and throw it inwardly, while the upper part by a reverse inclination throws it outwardly, or vice versa.

In Fig. 10 a further modification is shown, in which three blades to each beater, instead of two, are employed.

In defining my invention with greater clearness I would state that I am aware that it is not new to have two bowed beaters rotating on separate axial rods in close proximity to each other, the blade of one bow being so timed as to pass in its rotation between the blades of the other bow by means of gearing substantially the same as shown by me, and I do not claim this broadly. On the other hand, I am aware that an egg-beater has been provided with a blade whose plane occupies an inclined position to the radial line, and I do not claim this broadly. My invention consists, so far as this feature is concerned, in combining these two old features to produce an entirely new result by coöordinated action. Where a beater rotating about a single central axis has its blades inclined to the radial, its rotation soon causes the entire contents of the vessel to start in a whirling action, which from centrifugal action naturally causes the liquid to trend away from the beater and keep out of its reach and which stops all beating action. On the other hand, when there are two bowed beaters on independent axes, or axes eccentric to each other, but with blades that are not inclined to the radial,

there is an active commotion inside the range of the beaters; but there is no drawing of the material inwardly toward the center; but, on the other hand, centrifugal action will still assert itself and keep a certain amount of the material in the outer zone that is unbeaten and which will be found in the bottom of the vessel when the beater is removed. With my invention the two beaters preclude the continuous whirling and centrifugal action which a central set of inclined blades will produce, and at the same time it will continually draw every particle of the outlying zone of material into the center, where complete agitation exists, so that practically every particle of the material in the vessel will be converted into a frothy mass without any unbeaten liquid residuum.

Having thus described my invention, what I claim as new, and desire to secure by Letters Patent, is—

1. A beater consisting of two rotating bows arranged on independent axes side by side and eccentric to each other and having the blades of these bows set at an inclination to the radial line substantially as and for the purpose described.

2. A beater consisting of two rotating bows arranged on independent axes side by side and eccentric to each other and having the blades of these bows set at an inclination to the radial line, the inclination of the lower half of the blade being reverse to that of the upper half, substantially as and for the purpose described.

3. A dasher for a beater consisting of a circular ring with a single offsetting-shank both made in one piece the ring being bent to form inclined blades and the shank portion being curved in cross-section substantially as and for the purpose described.

4. In a beater, a handle consisting of a flat bar having its middle part bent into an elliptical bow, split longitudinally into twin diverging sections, and having between the split and divergent sections a flat metal plate connecting and staying the twin bows and forming a broad handhold substantially as and for the purpose described.

5. The combination with the two lower ends of the handle, and the two upper ends of the beater-shafts; of a spacing-block arranged between the lower ends of the handle and having recessed seats to receive the upper ends of the beater-shafts between the block and the lower ends of the handle-section, and one or more bolts passing through the handle-section and the block and clamping the upper ends of the beater-shafts between the same substantially as and for the purpose described.
